H. G. PAPE,
TELEPHONE HAND SET OR HAND PIECE,
APPLICATION FILED JUNE 24, 1918.

1,341,280.

Patented May 25, 1920.

Herman G. Pape

INVENTOR

UNITED STATES PATENT OFFICE.

HERMAN G. PAPE, OF NEW YORK, N. Y.

TELEPHONE HAND SET OR HAND PIECE.

1,341,280.

Specification of Letters Patent. Patented May 25, 1920.

Application filed June 24, 1918. Serial No. 241,642.

To all whom it may concern:

Be it known that I, HERMAN G. PAPE, a citizen of the United States, residing at New York, in the county of New York and State of New York, have invented certain new and useful Improvements in Telephone Hand Sets or Hand Pieces, of which the following is a clear description.

My invention relates to one piece types of hand micro-telephones and has for its objects, lightness, together with comfort and natural tonal results. For the accomplishment of these features, I have not overlooked the features of hygiene, durability, and low cost of production and maintenance. Besides, I have produced an instrument that will suit a person of either tall or low stature, or one that is either in a sitting or standing poise. Thus, through the production of this invention, I have also entirely dispensed with the use of the present-day desk bracket, so much required for use of desk sets of the well known (so called standard) American Bell type, where the receiver forms a separate part of the equipment, is fastened to a separate cord and must be suspended on the rest part of the equipment when in normal position.

A feature also of my invention is that of automatic switching or signaling as patent applied for in my application Ser. #879,012, Speaking and signaling apparatus, filed Dec. 26th, 1914, patented July 16, 1918, No. 1,272,993, with which this invention is therefore allied.

A further object of my invention is the provisioning of switching or signaling means in or to any electrical hand-set in such a way so as to avoid the necessity of separately mounted or provided switching means apart from the hand-set.

A further object of my invention is to so construct the same, so that the means whereby it is supported, also constitutes its line switching or signaling means.

A further object of my invention is to provide a hand-set in such a manner with legs or feet, so that it virtually itself becomes both stand and hand-set combined and able to be used, supported and operated in any convenient place, upon any conveniently handy support, or supports wherever provided for the purpose.

A further object of my invention is the provision of a very low and convenient gripping place on a hand-set carrying apparatus

at both ends, or provided with feet or other standing facilities as this hand-set, or with switching facilities similar to those here, so as to eliminate virtually all reaching or tiring poise to the user.

A further object of my invention is to provide for microphones of telephone hand-sets ample protective means that will permit of the simple housing and mounting of the microphone button in a manner as shown for instance in my Patents #1,025,992 and #1,236,103, and eliminating further the use of a mouthpiece, by acting also as sound collector or concentrator.

A further object of my invention is the provision of such mounting means for the microphone transmitter of a hand-set, as will permit rearward radiation or circulation of the sound and air waves of the speaker's voice as is explained in my Patent #1,025,992 and protected therein by claims #3, 5, 6 and 39.

A further object of my invention is the construction of an electrical hand-set or hand-piece with automatic switch so self-contained, so that, after the same has been taken in hand by a user and removed from its support, that it will not become a necessity to replace it to the same spot, support or place from where taken in order to switch it OFF, but that it will switch off as perfectly if placed to or upon any convenient means or provided support.

Another feature of my invention consists in the self-contained provision of automatic switching facilities in a hand-set or hand-piece in such a way, so that the same will switch ON when taken from support and will then remain ON while perhaps replaced, rested or supported in another manner, as for instance on or by its back.

With these features and objects in view and others as will be apparent, the invention comprises the various novel features of construction and arrangement of parts as will be more fully described hereinafter and set forth with particularity.

I wish it to be distinctly understood that the invention is not limited to the specific arrangement and organization of parts as shown and described, which will be seen also from the claims appended.

In the drawings:—

Figure 1 is a side view of my invention with the switch in the OFF position. Fig. 2 is a front view taken on the dotted line

3—4 of Fig. 1. Fig. 3 is a side view of the same switch as shown in Fig. 1, but shown in the ON position.

Like numerals represent like serving or equivalent parts.

Referring to the figures, 5 represents between the arrows 5^a and 5^b the hand-grip of the instrument. 5^c provides at X freedom to the small finger or fingers of the hand through providing extension in angular manner; thus facilitating convenient and low gripping of the device.

The member or plate 6 is provided with the following novel features: mounting projections 6^a, knobs serving the purpose of feet or legs 6^b and 6^{b'} and end-knock protection 6^c, serving the further purpose of collecting sound waves for the microphone transmitter 7 provided with a front-piece similar to that shown in my Patent #1,236,103.

8 represents the receiver or sound reproducer of the instrument with its earpiece 8' such as shown in my Patent #1,267,587. 9 represents the switching member for affecting the opening and closing of the talking or signaling circuit. It is operable by pressure from a point substantially right angular to the front or face of the instrument. 10 is a supporting ring or means by which the instrument when constructed as per Figs. 1 and 2, is often preferably supported or hung up by to the side of any perpendicular wall to which has been fastened a suitable hook, headed hanger or any other kind of suitable part or means such as shown at 11, the projecting length of which, from the surface of the wall to the underside of the head or hook is readily gaged, so that sufficient depression of the button or switching member 9 is insured to switch the instrument OFF when suspended thereby. 12 represents the usual transmitter cut-out button and 16 represents the connecting cord.

The switching member 9 constitutes a leg or foot, by means of which the instrument is supported or stood up. The switch being then in the OFF position.

The switching member 9 operates when a push and release motion is imparted to it. Thus it will be seen, that the signaling operation is but a simple matter while the instrument is in use, since it need not first be replaced somewhere, to some certain or special place; nor need a circuit switch that is contained in or about some other appliance first be looked for. A separate switch, such as a hook switch or cradle switch, used heretofore and to this day with desk telephone sets and other hand-sets, is not a requirement with my invention. It is self-contained in this respect.

In Fig. 1, line 1—2 represents between arrows a—b a horizontal or table line, and between arrows a—c a perpendicular or wall

line. Thus, when it is desired to suspend the instrument when not in use, it is only necessary to construct it with the hanger 10. If on the other hand it is desired to use or support the instrument from a desk or table, it is only necessary to construct it as shown in Fig. 1, with or without the hanger 10.

To operate the switch from the OFF to the ON position, it is only necessary to remove the instrument from its support while it is facing the support, whether hanging or lying. Likewise, to operate it from the ON to the OFF position, it is only necessary to place it to its support with its face facing the support.

By having the push switch of the instrument located on the face or front side of the instrument and in a right angular operating relation to its face, I have provided for great protection to both user and instrument. It will be noted, that thus the active parts of the instrument are less exposed to injury when the instrument is not in use or in its OFF position and that dust and dirt are not so readily collected on its face and through the openings or perforations thereof. Any such collection of dust or dirt would frequently be carried to the user's ear by the application of the earpiece thereto; or, from the microphone transmitter into his mouth or nose; besides, that the fine operation of the instrument would be most seriously hampered where the instrument is used in places where the air is ever filled with foreign particles.

By a great triangular spread of the feet or the support resting surfaces of the instrument, that are constituted by the knobs 6^b and 6^{b'}, and by the push member 9, I have produced an instrument that quickly finds its own level and one that stands rigid and firm on any support placed. It will be noted, that the feet or points of surface contact of the instrument, when the same is in its normal position of rest, are evenly distributed in an isosceles triangular manner, and that the switching member 9 is located at the acute angular point thereof.

What I claim is:

1. The combination with a hand-set of the type described and illustrated, of a switch having an automatic actuating member, said actuating member constituting one of a plurality of support contacting surfaces, means facilitating the instrument to be used as a combination wall or desk piece, said switch being only in the OFF position when the instrument is resting normally with its contacting surfaces against a perpendicular or upon a horizontal support, the actuating member being then depressed through said means and through gravity when said instrument is used hanging or as a wall instrument.

2. In combination with a hand-set of the

- type described and illustrated, comprising two or more projecting contact surfaces or feet, one of said feet constituting an actuating member of an automatic gravity switch, 5 a hanger, said switch being only in its OFF position when depressed or when said hand-set is perpendicularly suspended by its hanger in its normal position of rest, and being also only in its OFF position when 10 50 said hand-set is horizontally rested by its projecting contact surfaces comprising the actuating member upon a horizontal support, said actuating member being depressed by the instrument's own gravity.
- 15 3. In combination with a hand-set of the type described and illustrated, comprising two or more resting surfaces or feet, one of said resting surfaces constituting the actuating member of an automatic gravity 20 55 switch, a hanger, said switch being only in the OFF position when said hand-set is suspended by said hanger in a manner substantially perpendicular against an upright by its own gravity and when its face or a 25 60 certain one of its sides only is facing the upright, said switch being also only in the OFF position when the hand-set is rested in substantially horizontal manner upon a support with its face or that same side facing the 30 65 support that faces the upright when said switch is in OFF position.
4. A telephone hand-set comprising a handle, a microphone and a receiver, movable or yielding means of support forming an integral part of the hand-set, one of said means 35 70 constituting a switching or signaling member, said microphone being provided with a sound collector, said sound collector constituting also a means whereby the instrument 40 75 is rested to its support.
5. In combination with a hand-set of the type described and illustrated, comprising a switch that is in its OFF position when its actuating member is depressed, an upright 45 80 with a hook or other means of suspension whereby the actuating member is depressed by way of the instrument's own gravity, said switch being also operable by hand for signaling purposes, and operable to OFF 50 85 position when used as a desk or table instrument upon the top of a desk, table or other substantially horizontal resting or supporting means, said instrument being only in OFF position while facing the upright or 55 90 horizontal supporting means with its face or with a certain one of its sides.
6. The combination with a hand-set of the type described and illustrated, comprising a gravity switch, means facilitating the instrument 60 95 to be used as a combination wall and desk piece, said switch being in OFF position only when the instrument is placed with a certain side or face to its upright support, and being also only in the OFF position 65 100 when placed with that same side or face rest-
- ing upon a substantially horizontal support such as the top of a desk, table, or other flat surface.
7. In combination with a hand-set of the type described and illustrated, comprising two or more feet or resting surfaces located on the open or face side of the instrument for both horizontal and perpendicular resting purposes, one of said feet or resting surfaces constituting the actuating member of a 70 105 switch, a hook, headed part, or means, for forcing the switch into OFF position through the instrument's own gravity when perpendicularly suspended against a substantially upright means.
8. A telephone hand-set comprising a handle, a transmitter mounted to one end of the handle, a receiver mounted to the other end of the handle, a sound concentrator constituting a foot or supporting surface contacting means, an automatic switching member located at one of the remote ends of the hand-set and constituting the acute point of a substantially isosceles triangular outlay of the supporting surface contacting means, 80 110 said contacting means being on the face side of the instrument.
9. In combination with a hand-set of the type described and illustrated, comprising two or more feet or resting surfaces one of which constitutes a switching member, a hook, headed, or upturned hanger comprising a means for forcing the switching member into its OFF position when the instrument is perpendicularly suspended.
10. In a telephone hand-set, a micro-telephone transmitter, a receiver, a mounting comprising a handle and end-knock protectors or bumpers, said protectors constituting feet, one of said protectors or feet housing the actuating member of an automatic switch.
11. In a telephone hand-set, a micro-telephone transmitter, a receiver, a mounting comprising a handle and end-knock protectors or bumpers, said protectors constituting feet or surface rests, one of said protectors or surface rests constituting also a sound collector for the transmitter.
12. In combination with a hand-set of the type described and illustrated comprising a switch that switches OFF when depressed, a means of perpendicular suspension and in association therewith a hooked or headed part or means for forcing the switch into its OFF position when the instrument is suspended in its normal position of rest.
13. A telephone hand-piece of the self-contained automatic switching style as described and illustrated, comprising a handle, a transmitter, a receiver, end-knock protectors or bumpers, one of said bumpers housing the actuating member of a depressible gravity switch on the front or face side of the instrument, said switch being in the OFF 120 125 130 position.

- position when said actuating member is depressed, one of said bumpers constituting a sound deflector for said transmitter, and said handle being humped to facilitate a low grip of the instrument and to prevent a tiring arm poise of the user.
14. In a telephone set, a micro-telephone transmitter, a mounting disk with mounting projections or raised portions for said transmitter, said raised portions permitting rearward radiation or play of waves between the rear of said transmitter and said mounting disk, and a handle for said mounting disk.
15. In a telephone hand-set, a handle, a receiver, a micro-telephone transmitter, a mounting for said transmitter, said mounting being provided with means permitting rearward radiation or play of waves be-
- tween the rear of said transmitter and said mounting.
16. In a telephone, a micro-telephone transmitter, a receiver, a mounting, said mounting being provided with extensions comprising feet or surface rests, one of said feet constituting an actuating member of a switch, and means for said mounting permitting rearward radiation or play of sound or air waves between the rear of said transmitter and said mounting. 30

Signed at New York, in the county of New York and State of New York, this 21st day of June, A. D. 1918.

HERMAN G. PAPE.

Witnesses:
